Jacob Shieberman

ATTORNEY

UNITED STATES PATENT OFFICE.

FREDERICK K. MAERZ, OF EAST CLEVELAND, OHIO, ASSIGNOR TO THE MILLER COMPANY, OF MERIDEN, CONNECTICUT, A CORPORATION OF CONNECTICUT.

DESIGN FOR A WALL BRACKET.

Application filed September 1, 1926. Serial No. 18,922. Term of patent 3½ years.

To all whom it may concern:

Be it known that I, FREDERICK K. MAERZ, a citizen of the United States, residing in East Cleveland, in the county of Cuyahoga and State of Ohio, have invented a new, original, and ornamental Design for Wall Brackets, of which the following is a specification, reference being had to the accompanying drawing, forming a part thereof.

The figure is a perspective view of the wall bracket made according to my design.

I claim:

The ornamental design for a wall bracket, as shown.

FREDERICK K. MAERZ.
